Vincenzo Speziale,*

By J. Stuart Freeman,
Attorney.

UNITED STATES PATENT OFFICE.

VINCENZO SPEZIALE, OF MILLVILLE, NEW JERSEY.

SWIMMING DEVICE.

Application filed May 13, 1927. Serial No. 190,987.

The object of the invention is to provide improvements in means to assist persons in the water to swim in various ways, or to "tread water" as the case may be, and to afford assistance in life-saving operations.

Expert swimmers it is well known benefit more than do amateurs from the natural surfaces available upon the hands and feet for treading upon or pushing against the water, and it is to overcome this apparent deficiency of amateurs that the present invention is designed.

Another object therefore is to provide frame structures adapted to be securely, yet removably at will, attached to the lower limbs, and embodying in their construction pivotally mounted vanes which trail through the water as the limb is moved forwardly, but which present a relative flat surface to the water as soon as the limb is kicked backwardly, whereby said vanes offer substantially no water resistance in one direction, but a maximum of such resistance when moved in the opposite direction, added to the natural effective surface of the bottom of one's foot.

A further object is to provide a device of this character which is of low cost of manufacture yet a high degree of efficiency; a device in which the individual vanes can be readily replaced when broken, or otherwise damaged; as well as a device which at all times occupies a minimum of space when removed from the leg, and extends a minimum distance laterally from the leg when operatively associated therewith.

And a still further object is to so construct the device as to make a single size adaptable for use by persons of various heights and having limbs of similarly varying sizes, while the means for varying the length of the device is incorporated with pivotal means for permitting the foot portion to oscillate with respect to the upper portion, as the foot during certain motions of swimming oscillates with respect to the lower leg about the ankle.

With these and other objects in mind, the invention comprises further details of construction and operation fully brought out in the following description, when read in conjunction with the accompanying drawings, in which Fig. 1 is a side elevation of a person's left lower leg and foot equipped with one embodiment of the invention with the vanes in retracted positions; Fig. 2 is

a front view of the same with the extended positions of the vanes shown in dot-and-dash lines; Fig. 3 is practically a side view of Fig. 1, but showing the foot extended so that the two pivotally connected portions of the device are angularly related; and Fig. 4 is an enlarged section on the line 4-4 of Fig. 1.

Referring to the drawings, there is shown a framework comprising two elongated members 5 and 6, provided with spaced apertures 7, and adapted to be adjustably and pivotally connected by means of a removable bolt 8. The upper of said members 5 is provided with lateral extensions 9 slightly curved transversely in order to fit against and conform to the curvature of the upper part of the lower limb, the free end portions of said extensions being provided with straps 10, adapted to be adjustably connected together and thereby secured about one's limb by means of a buckle 11 or the like. Attached to the member 5-9 or forming an integral projection is an upwardly extending plate portion 12, preferably provided with an outwardly extending bracket 13, having an angular portion 14 unitarily secured in any suitable manner to the plate 12, while the free end portions of said bracket and said angular portion are connected by a brace 15.

Pivots secured at 16 to the frame extensions 9 in any suitable manner is a substantially kidney-shaped vane 17, shaped so that its opposite end portions 18 extend laterally in the plane of the central portion 17, partially around the limb, when the vane is in the extended operative position shown in dot-and-dash lines in Fig. 2. It will be obvious from an examination of this figure that as the foot of the swimmer is drawn upwardly, that his knee approaches his chin or chest, the rearward rush of water oscillates the vane into the position shown in Figs. 1 and 2, wherein the vane offers a minimum resistance to the flow of the water. However, as soon as the swimmer kicks his limbs rearwardly, or downwardly when in the art of treading water, the relative reverse direction of the flow of water catches the vane and oscillates it into the dot-and-dash position shown in Fig. 2, wherein the vane offers a maximum resistance to the water and provides an increased effective surface to aid in swimming, since the average swimmer not equipped with any such device as that com-

prising the present invention relies substantially only upon the surface area of the under side of his foot.

The lower frame member 6 is provided with lateral extensions 20 and 21, to which is pivotally secured at 22, a vane 23, of the same general shape as the vane 17, and having laterally extending terminal projections 24, corresponding with the extensions 18 of said first-named member. The member 6 is furthermore provided with a transversely widened portion 25, provided with brackets 26, attached to said portions by means of an integral extension 27 and its rigidity insured by means of a brace 28, the elements 26, 27 and 28 corresponding with the similarly shaped elements 13, 14 and 15, carried by the plate portion 12 of the member 5. The member 6 is furthermore provided with a longitudinally and normally downwardly extending projection 29 which forms a stirrup and is rounded beneath the instep of the foot 30, and at its opposite free end is connected by means of a strap 31 with one of the two straps 32, connected with the lateral extensions 20 and 21, and which latter are normally adjustably connected by means of a buckle 33. The stirrup extension 29 may furthermore be secured to the forward portion of the foot by means of adjustably connected straps 34, though this is not absolutely essential to the operation of the device.

It should be noted that while the vanes 17 and 18 can be constructed of any desired material and of any shape which will provide a maximum surface when in operative position, it is obviously desirable, when not too expensive, to form them of spaced sheet metal disks 35, having an air chamber 36 between them if desired and curved together and united in water-tight relation along their marginal portions 37. However it is the broad principle of construction involved and not the relatively minor details in which the applicant is primarily interested and it is in this light that the appended claims are to be considered.

By referring to Fig. 3, it will be seen that as persons equipped with this invention straighten out their feet when walking both in the water or on land, and as the knee is drawn upwardly while swimming, the pivotal connection 8, between the members 5 and 6, provides for this angular movement and thus does not in any way hinder the free oscillation of the foot whenever the same may be desired. Furthermore, from the connection hereinbefore described, it is

obvious that by removing the bolt 8 and replacing it through any desired pair of the apertures 7 in the overlapping members 5 and 6, the longitudinal distance between the arm extensions 9 of the member 5, and the extensions 20 and 21 of the member 6 are varied so that the device is adapted to fit various sizes of limbs and accordingly persons of widely differing heights.

Having thus described my invention, what I claim and desire to protect by Letters Patent of the United States is:

1. A swimming device, comprising two pivotally connected members, a vane pivotally supported by each leg member, means to limit the movement of each vane in one direction, and means to secure the device to the leg of a swimmer.

2. A swimming device, comprising two members each having a series of perforations, means to pivotally and adjustably connect said members through said perforations, a vane pivotally carried by each of said members, and means to limit the movement of each vane in one direction.

3. A swimming device, comprising two members adjustably and pivotally connected, each member having a transversely widened portion, a vane pivotally carried by each of said members, and brackets carried by each of said widened portions to limit the movements of the respective vanes in a given direction.

4. A swimming device, comprising two members adjustably and pivotally connected, each member having a transversely widened portion, a vane pivotally carried by each of said members, brackets carried by each of said widened portions to limit the movements of the respective vanes in a given direction, and flexible means to adjustably and removably secure each of said members to the leg of a swimmer.

5. A swimming device, comprising two members adjustably and pivotally connected, each member having a transversely widened portion, a vane pivotally carried by each of said members, brackets carried by each of said widened portions to limit the movements of the respective vanes in a given direction, one of said members being extended longitudinally in one direction to form a stirrup, and flexible means to adjustably and removably secure said members and said stirrup to the leg of a swimmer.

In testimony whereof I have affixed my signature.

VINCENZO SPEZIALE.
